HERBERT B. TAYLOR, OF ROCHESTER, NEW YORK, ASSIGNOR TO GENERAL RAILWAY SIGNAL COMPANY, OF ROCHESTER, NEW YORK

ELECTRICAL PLUG COUPLER

Application filed October 15, 1926. Serial No. 141,864.

This invention relates to electrical plug couplers and more particularly to a coupler for use on a locomotive equipped with automatic train control.

On locomotives equipped with automatic train control usually part of the electrical equipment is located on the engine and part on the tender, and it is desired to have means whereby the electrical connections may be 10 quickly and easily broken and re-established before and after repairs are made. For instance it is desirable to have a plug connection for the circuits leading to the influence communicating receiver which receives control influences from the trackway, and which is usually mounted on the tender, so that the electrical connection may be broken easily when it is found necessary to dismount the receiver for repairs.

20 At times when the engine is disabled, it is common practice to change engines and use the same tender and by having a plug connector between the engine and tender, the electrical circuits between the two can be 25 readily disconnected, a new engine substituted and the circuits re-established in a very short time.

In view of the above mentioned objects and requirements it is proposed to provide a quick 30 detachable electrical plug coupler of durable construction suitable for use on railroad trains.

Other objects and characteristic features 35 of the invention will be pointed out herein- after as the description progresses. In de- scribing the invention in detail, reference will be made to the accompanying drawing in which:—

Fig. 1 is a plan view of the quick detach- 40 able plug coupler with certain parts broken away for clearness;

Fig. 2 is a section taken on the line 2—2 of Fig. 1;

Fig. 3 is an end view showing the construction and mounting means of the plug coupler shown in Figs. 1 and 2;

Fig. 4 is an enlarged plan view showing the lower contact block and contact posts;

Fig. 5 is an enlarged section taken on the 50 line 5—5 of Fig. 4 showing the construction

of the lower contact post and part of the co- operating upper contact post.

The plug coupler as a whole is made up of two units designated A and B on the drawing, which units are held together by a tie bolt C. 55 Unit A comprises a casing having a contact block mounted therein, this casing having various threaded holes therein for coupling the conduits thereto, these conduits carrying the wires to be connected by the coupler to other wires. This casing is also provided with means for mounting the complete block coupler to the engine or tender as the case may be. Unit B comprises a casing which also has a contact block mounted therein and is provided with threaded holes for conduit connections. 60

Referring more particularly to Figs. 1, 2 and 3 of the drawing the casing 1 comprises the main body or unit A. This casing has four projecting lugs 6 around the inside thereof, and to these lugs is fastened a contact block 2. One of these lugs 6 has a dowel pin 4 fastened therein which is adapted to project through a hole in the contact block 2. 70 This dowel pin is used for locating the contact block in the casing with respect to the various binding posts. The contact block 2 is then fastened securely to the other three lugs with screws 7. Mounted on this contact block is a series of binding posts 3, each being provided with lock nuts and clamping nuts and washers. The lower ends of the binding posts 3 have enlarged heads 5, these heads being wedge shaped to spread apart and make good contact with the contact fingers mounted in the lower casing B, as de- scribed hereinafter. The casing 1 is pro- 75 vided with circular openings at the top and bottom as shown on the drawing. A cover 8 is placed over the top opening, this cover being fastened securely with screws 9. Mounted transversely therein and threaded into this cover 8 is a tie bolt C, this tie bolt being peened over on the outer surface to 80 keep the bolt from turning in the cover after it is once in place. Lugs 32 having holes 33 therein are provided on the casing 1, these lugs being used for mounting the complete 85

coupler on the locomotive. As men- 90

tioned before, various threaded openings 10 are provided for attaching the conduits.

Unit B of the plug coupler comprises a cylindrical casing 11 which has inwardly projecting lugs 12 similar to those used in the upper casing 1. Mounted on these lugs 12 is a contact block 13 fastened with screws 14 and a dowel pin (not shown) as described before in connection with the upper casing 10. 1. This casing 11 also has a large circular opening in each the top and bottom wall thereof, and is provided with a cover 20 over the lower opening, this cover being fastened in place with screws 21. Threaded openings 10 are provided for attaching the conduits thereto. On the contact block 13 is mounted a series of contact fingers adapted to engage the wedge shaped heads 5 of the upper binding posts 3 described hereinbefore. 20 These contact fingers (see Fig. 5) each comprise a binding post 15 having an enlarged square head to which are riveted two upwardly projecting fingers 16, these fingers being rounded out and turned in to form a pocket 25 for the wedge shaped heads 5 of the binding post 3. This contact post 15 has an upwardly projecting cylindrical portion 17. A cup shaped sleeve 18 is provided which is adapted to fit over and telescope on this upper projecting portion 17. Inserted between the head of this sleeve 18 and the head of the contact post 15 is a coil spring 19, this spring biasing sleeve 18 upward. It can readily be seen by referring to the drawing that when 30 the upper unit A and the lower unit B are assembled the wedge shaped heads 5 of the binding posts 3 will wedge in between the contact strips 16 of the binding posts 15 and will also press against the heads of the sleeves 35 18, compressing the spring and thereby making a good contacting connection. These contact posts 15 are also provided with clamping units, lock nuts and washers for fastening the wires thereto. It should be noted that 40 the contact blocks 2 and 13 are provided with countersunk squared openings adapted to receive the squared heads of the contact posts 3 and 15, this arrangement preventing the contact posts from turning once they are 45 in place and the clamping nuts securely tightened.

Referring now more particularly to Figs. 1, 2 and 3, when assembling, the lower unit B is fastened to the upper unit A by the tie bolt C as mentioned hereinbefore, suitable openings 22 being provided in the contact blocks 2 and 13 to permit the passage of this tie bolt therethrough. An insulated sleeve 25 is preferably inserted in the unit A and 50 around the tie bolt C, this being done to prevent the wires from rubbing against the tie bolt and possibly causing a short circuit. Gaskets 26 are provided between the casings and covers, and a gasket 27 is used around 55 the opening in the cover near the lower end

of the tie bolt C so that all joints will be water tight. A nut 28 and washer 29 are placed on the lower end of this tie bolt so that casings may be clamped tightly together.

When it becomes necessary to break the connections of this plug coupler, means is provided whereby this coupler may be reassembled and have all connections in their original places. This is done by having a projecting lug 30 on the casing of the lower unit B, this lug 30 sliding in a notch which is provided in the rib or skirt 31 extending around the lower part of the casing 1. It can readily be seen that when it becomes necessary to break the electrical connections, the nut 28 and washer 29 only need be removed when the lower unit B can then be pulled away from the upper unit A, without disturbing the order of the wires or conduit connections in either unit.

Although this plug coupler has been described in connection with the use of automatic train control on locomotives it is desired to be understood that it could be used to advantage in various other places where it is desired to have a break in a circuit wherein the wires are subjected to strains and vibrations. Also, it should be understood that this form of plug coupler should not be limited to eight connections as shown and described but could have either more or less connections as desired without departing from the design and scope of the invention shown and illustrated.

What I claim is:—

A quick-detachable connector for electric circuits, comprising, a two part casing, means for insuring its proper assembly, a female portion in the casing including, two opposed flat spring clips, spaced apart and having in-turned free ends facing each other to form a narrow slot therebetween, a fixed post spaced from, and in line with, said narrow slot, a sleeve slidably carried on said post with a flat face, and a spring biasing said sleeve to press said face against the ends of said spring clips, and a male portion in the casing including a flat sided wedge tapering toward its free end and adapted to enter between, and spread, said clips.

In testimony whereof I affix my signature.

HERBERT B. TAYLOR.
